UNITED STATES PATENT OFFICE.

BERNHARD JOHN VALENTINE ADOLPH FLUGEL, OF LONDON, ENGLAND.

TYPE-WRITING MACHINE.

1,027,717.

Specification of Letters Patent.

Patented May 28, 1912.

Application filed December 22, 1909. Serial No. 534,517.

To all whom it may concern:

Be it known that I, BERNHARD JOHN VALENTINE ADOLPH FLUGEL, manufacturer, a subject of the King of Great Britain, residing at 21 Lime street, in the city of London, England, have invented certain new and useful Improvements in or Relating to Type-Writing Machines, of which the following is a specification.

10 This invention has for its object to provide type-writing machines with a special key-actuated carriage return.

According to the present invention means for returning the carriage are so combined and arranged to act in conjunction with the typewriting machine that upon the end of the line being reached (*i. e.* upon the carriage reaching the end of its travel to the left) thereupon the return-key will release 20 the carriage from the devices which normally hold the said carriage in position and also release or bring into operation the usual motor by which the carriage is returned along its guideways to the extreme right 25 hand position for which the machine may be set for the time being. The turning of the roller for feeding the paper may then be separately and independently effected in the usual manner.

30 I will now proceed to describe my present invention with reference to the accompanying drawings, in which the figure shows a side elevation of the invention.

The toothed wheel A adapted to rotate 35 freely around the shaft *a* is driven by any suitable motor such as an ordinary spring clockwork motor (not shown) mounted on the main frame or other fixed part of the typewriting machine and this wheel A 40 gears with the toothed wheel B adapted to rotate freely around the shaft *b* and this latter wheel B in turn gears with the smaller toothed wheel C adapted to rotate freely around the shaft *c* in opposite direction to B. The shafts *b* and *c* are carried 45 in the yoke-ends or forked ends D¹ D² of the yoke-lever or rocking-lever D which latter is pivoted or adapted to rock or turn through part of a circle, around the aforesaid shaft *a* of the motor driven gear wheel A.

The rocking lever D at its end *d* is normally kept pressed in one direction (*i. e.* in the direction of the arrow *x*) by the spring E; and means are provided such as the rod F to force the end *d* of said rocking-lever

D in the opposite direction to said arrow *x*; the spring E keeping said end *d* of said lever D forced against the collar or abutment *f* fixed on the rod F which latter in turn has a fixed limit of movement forming its normal position and when in this normal position (as shown in the drawings) the end *d* of the rocking-lever D is moved to its extreme right hand position against said abutment *f* by the action of the spring E and thereby the toothed wheel B is forced into gear with the teeth of the rack H which is thereby moved along—in the direction of the arrow *y*—space by space (*i. e.* one space 70 at a time) as and when any key of the type-writing machine is operated; or a fixed number of spaces for tabulating purposes; while on forcing the end *d* of the rock lever D in the opposite direction to the arrow *x* through the medium of the rod F thereby the toothed wheel B is moved out of gear with the toothed rack H and the toothed wheel C simultaneously moved into gear with the teeth of said rack H which latter 80 is thereupon caused to automatically return in one movement to the limit of its travel in the direction of the arrow *z* whereupon on releasing the rod F the spring E will rock the lever D and move the toothed wheel C out of—and the toothed wheel B again into—gear with the teeth on the rack H.

The rack teeth or toothed rack H may either be formed on, or separately formed 90 and mounted on the carriage or traveling support carrying the platen or roller or means over or against which the paper or other material is held while being struck by the type; for example these rack teeth may be formed in a rack-bar such as H and this rack bar H may be rigidly fixed to the aforesaid traveling carriage (not shown) by means of the arms or brackets I and J.

1 L is a carriage return-key operating solely 100 for the purpose of actuating the returning means of the carriage.

What I claim is:—

1. A device of the character described, comprising a rocking-lever adapted to be 105 pivotally mounted on the frame of a type-writing machine, a pair of intermeshing toothed wheels rotatably mounted on the rocking-lever, means operated by a motor for rotating said toothed wheels, a rack attached to the typewriter-carriage and adapted to be engaged by either of said

2
toothed wheels, means for normally pressing the rocking lever in one direction to cause one of the toothed wheels to engage the rack, and means for moving at will the 5 rocking lever in the opposite direction to cause the other toothed wheel to engage the rack.

2. A device of the character described, comprising a main-axle adapted to be 10 mounted on the frame of a typewriting machine, a drive gear wheel rotatably mounted on said main axle and adapted to be driven by a suitable motor, a Y-shaped rocking-lever pivoted on said main axle, a large toothed 15 wheel pivotally mounted at the end of one arm of the rocking-lever and intermeshing with the drive gear wheel, a smaller toothed

wheel mounted at the end of the other arm and intermeshing with the larger toothed wheel, a rack adapted to be attached to the 20 typewriter carriage and to be engaged by either of said toothed wheels, a spring pressing against the end of the main stem of the rocking-lever and causing one of said toothed wheels to normally engage said 25 rack, and means for moving said main stem against the pressure of the spring to cause the other toothed wheel to engage the rack.

In witness whereof I have hereunto set my hand in presence of two witnesses.

BERNHARD JOHN VALENTINE ADOLPH FLUGEL.

Witnesses:

EDWIN GANDER,
CARL R. Loop.
